(57) **CLAIM**

The ornamental design for a case for electronic device, as shown and described.

DESCRIPTION

FIG. 1 is a perspective view including a front, top and one side of an embodiment of the case for electronic device; FIG. 2 is a front elevation view of the case for electronic device of FIG. 1; FIG. 3 is a rear elevation view of the case for electronic device of FIG. 1; FIG. 4 is a side elevation view of the case for electronic device of FIG. 1; FIG. 5 is an opposite side elevation view of the case for electronic device of FIG. 1; FIG. 6 is a top plan view of the case for electronic device of FIG. 1; and, FIG. 7 is a bottom plan view of the case for electronic device of FIG. 1. The broken lines depict portions of the case for electronic device that form no part of the claim.
